U. S. PATENT OFFICE

ARTHUR C. CANDLAND, OF PROVO, UTAH.

AUTOMATIC RAIL-FASTENER.

1,023,322.

Specification of Letters Patent. Patented Sept. 24, 1912.

Application filed July 2, 1912. Serial No. 708,372.

To all whom it may concern:

Be it known that I, ARTHUR C. CANDLAND, a citizen of the United States, residing at Provo city, in the county of Utah and State of Utah, have invented certain new and useful Improvements in Automatic Rail-Fasteners, of which the following is a specification.

My invention relates to railway ties and means to fasten the rails on the tie; and has for its object to provide a simple form of channel tie and fastening means to securely hold the rails in place on the tie. The rails are securely held in place and the fastening means are automatically tightened by the jar of the passing trains.

A further object is to provide a track that is simple in construction, efficient in operation and economical in manufacture and laying.

These and other objects, which will be readily apparent, I accomplish with the device illustrated in the accompanying drawings in which similar letters of reference indicate like parts throughout the several figures, and as described in the specifications forming a part of this application, it being understood that slight modifications in form may be resorted to within the scope 30 of the claims without departing from the spirit of the invention.

Figure 1 is a perspective view of one end of a tie with a part of a rail secured with my fastening means, parts cut away. Fig. 2 is a plan view of one end of the tie with one key in place therein. Fig. 3 is a vertical section on line $\alpha-\alpha$ of Fig. 1. Fig. 4 is a perspective view of one of the bell crank levers and a cross section through said lever. Fig. 5 is a front elevation and plan view of one of the locking wedges. Fig. 6 is a front elevation and plan view of one of the keys.

Fig. 7 is a view in perspective of one of the rail clamps. Fig. 8 is a view in perspective of one of the cushion blocks. Fig. 9 is a view in perspective of one of the locking blocks.

My tie is cut from a sheet of metal and bent to form a channel 1. At the point where it is intended to have the rails cross the tie, the sides of said channel are slit and portions of the sides are bent outwardly to form lugs 2, in each of which is cut an opening or slot 3. In the free side of each of said lugs 2 and for closing said opening or slot 3 is fitted a key 4, purposely cut in

wedge form so that it will fit into an angled mortise forming a part of the opening 3 in said lugs 2, which key will readily adapt itself to being moved upward, but will seat in said mortise and hold a locking block 5 in said slot 3. Within said channel and between the lugs 2 are placed rail supporting blocks 8 made of wool or fibrous material.

Within said channel and adjacent said rail supporting blocks 8 are transversely fitted clamps 9, each having a portion 10 thereof extended to grip the base flange of a rail, and another portion 11 extended to lock the bell crank levers 6 in place. In the sides of said channel, and preferably before the same is bent to form the channel, are cut open slots 12 opening into the slits by which the lugs 2 are cut in form. Before said clamps 9 are placed in position within the channel 1, a projecting pin 13, secured in each of said bell crank levers 6, is fitted within said open slots 12, which pin forms the fulcrum of said bell crank levers. Said pins 13 have cylindrically formed heads 14 thereon to prevent the pivot pins 13 of the said bell crank lever 6 from lateral removal from said cuts 12, and also to aid in holding said clamps 9 in place within the channel 1. The pivot pins 13 in said bell crank levers permit said levers being turned thereon in position to allow said clamps to enter the channel and engage the flange of the rail. The bell crank levers are then turned on their pivots 13 until the arms 7 of said levers engage the portions 10 of said clamps 9. The wedges 15 are then inserted between the lower end of two of said bell crank levers 6, one of said wedges on each side of the channel 1. Each of said bell crank levers 6 has its lower portion cut at an angle opposed to the angled edges of the wedges 15, with the acute angle of said portion extended outwardly, thereby forming a lock against lateral removal of said wedges 15, which wedges are held in place by gravity and in contact with said bell crank levers 6 and contiguous to the sides of the channel 1.

When said locking wedges 15 are in place, a locking block 5 is inserted within the slot 3 of the lugs 2 and of vertical thickness sufficient to bear on the upper side of said wedge 15 and in contact with the bottom of a rail. The keys 4 are then inserted within their angled mortise seats to prevent the unintentional withdrawal or displacement of said locking blocks 5. As will be

readily apparent any jar or pressure on the rail will drive or force the wedges 15 vertically downward and press the lower portions of the said bell crank levers 6 outward, and the arms 7 of each of said bell crank levers will be held in gripping contact with the clamps 9 and thereby hold the rails in place. To remove the rails, the keys 4 are raised and removed from their seats. The locking blocks 5 may then be taken out. This will leave the wedges 15 free to upward movement and they may be taken from between the depending arms of said bell crank levers 6. By turning the said levers on their pivots 13 the clamps and rails are released.

Having thus described my invention, I desire to secure by Letters Patent and claim:

- 20 1. A railway tie and fastener consisting of extended lugs cut from the sides of an upturned metal channel each of said lugs having an open longitudinal cut therein with its ends widened outwardly by beveled cuts; the slots adapted to receive locking blocks and the beveled cuts to form a seating mortise; a key adapted to seat in said mortise; bell crank levers pivoted to the sides of said metal channel; depending arms thereon beveled toward said channel; wedges having their side edges formed at an opposed angle to that on said bell crank levers; clamps transversely fitted in said channel having a portion of each bent to engage the base flange of a rail; cushion blocks to support a rail above said lugs; and a locking block between said rail and each of said wedges.
- 25 2. In a railway tie and fastener therefor the combination of portions of the sides of said tie bent outwardly to form lugs having open slots cut longitudinally therein, and other open slots in the sides of said tie adjoining said lugs; rail supporting blocks adjacent said lugs; clamps transversely placed in said tie, each having a portion bent to engage the base flange of a rail; bell crank levers detachably pivoted to the

sides of said tie each having one arm beveled and the other adapted to engage the rail engaging portions of said clamps; wedges 50 having each side edge beveled to engage the said bell crank levers; locking blocks adapted to fit within said open slots in said lugs, and prevent the unintentional removal of said locking blocks.

3. In a railway tie and fastener the combination of portions of the sides of said tie bent outwardly to form lugs, each lug having open slots longitudinally cut therein adapted to receive keys and locking blocks; bell crank levers detachably pivoted to the sides of said tie each having one arm beveled and the other arm bent to grip the base flange of a rail; wedges having their side edges beveled to engage the said bell crank 65 levers; and locking blocks adapted to be placed in the slots in said lugs and between said wedges and a railway rail.

4. A railway tie and fastener consisting of bell crank levers pivoted without and to 70 the sides of said tie; an arm thereon adapted to engage the base flange of a railway rail; wedges vertically placed to engage between the depending arms of two opposed bell crank levers; and means to prevent the 75 unintentional withdrawal of said wedges from between the said levers.

5. A railway tie and fastener consisting of bell crank levers detachably pivoted without and in pairs to the sides of a railway 80 tie; an arm on each of said levers adapted to grip the base flange of a rail; wedges adapted to vertically engage between the depending arms of each pair of said levers; and means to prevent the unintentional withdrawal of said wedges from between said levers.

In testimony whereof I have affixed my signature in presence of two witnesses.

ARTHUR C. CANDLAND.
